Primary Examiner—Paula Greene(74) *Attorney, Agent, or Firm*—Vidas, Arrett & Steinkraus, P.A.(57) **CLAIM**

The ornamental design for a wireless ear worn microphone transmitter, as shown and described.

DESCRIPTION

FIG. 1 is a perspective view of the wireless ear worn microphone transmitter;

FIG. 2 is a side elevation view of the wireless ear worn microphone transmitter;

FIG. 3 is a front top plan view of the wireless ear worn microphone transmitter;

FIG. 4 is a front bottom plan view of the wireless ear worn microphone transmitter;

FIG. 5 is a back top side plan view of the wireless ear worn microphone transmitter; and,

FIG. 6 is a back bottom side plan view of the wireless ear worn microphone transmitter.

The broken lines form no part of the claimed design.
